TUYÈRE AND NOZZLES

Humphrey A. Ellis, Philadelphia, Pa.

Application November 9, 1931, Serial No. 573,861

10 Claims. (Cl. 110—44)

The object of the invention is to provide improvements in the method and apparatus by which fine coal and similar fuels are burned, towards the end of obtaining greater efficiency than has heretofore been possible, and hereinafter the term tuyère plate will be uniformly employed to embrace and indicate the multi-channel unit, while the term tuyère will be used to designate the individual nozzles formed by one or more tuyère plates, except in such instances as when channels are referred to as such.

A further object is more specifically to provide a tuyère plate in which the individual channels, or pairs of channels, set up rotary or swirling currents of air, instead of the rectilinear jets from tuyères of the usual construction, which jets permit the air currents discharged under pressure to blow away from the bed formed of a plurality of tuyère plates much of the fuel which should be burned thereon, there being insured an emission of an even greater volume of air from the improved tuyères than from the straight channelled tuyère plates heretofore used, but without tending to disrupt or in any way disturb the fuel upon the bed within the range of all usual pressures of the air supplied.

In this way the improved tuyère plate is designed to accomplish results similar to those resulting from the use of the improved grate bar covered by Patent No. 1,701,150, the tuyères however diffusing air substantially horizontally through a usually sloping bed of fuel, while the grate bar is designed to diffuse air currents upwardly through a substantially flat fuel bed, in each case a greatly increased quantity of air being available at the usual pressures employed for full combustion, but without mechanically disturbing the position of the fuel itself.

Another object is to so design the improved tuyère plate that it can be cast inexpensively and without requiring the heretofore necessary coring, with consequent loss through imperfect formation of the several channels, while the improved type of air-swirl channels radiate in converging pairs about the normally exposed end portion of the tuyère, and thereby insure the diffusion of air substantially uniformly into all parts of the fuel body.

With these and other objects in mind, the invention comprises additional details of construction and operation, which are fully brought out in the following description, when read in conjunction with the accompanying drawing, in which Fig. 1 is a bottom plan view of one embodiment of the invention, the top of the tuyère

plate being preferably flat and unbroken except for apertures as hereinafter described; Fig. 2 is a side elevation of the improved tuyère plate shown in operative position upon a properly apertured disc, and by dot-and-dash lines in the position which it assumes in order to be released from such disc or supporting tuyère plate; Fig. 3 is a vertical section on the line 3—3 of Fig. 1; and Fig. 4 is a front elevational view of a fragmentary portion of the device.

Referring to the drawing, a tuyère plate comprising one embodiment of the invention is shown as resting operatively upon a base member 1, which may also represent a lower tuyère plate in a diagonally upwardly extending series. This base (or lower tuyère plate) is provided with a substantially T-shaped aperture 2, comprising a relatively narrow portion 3, tapering in one direction to a point 4 and opening in the other direction into a transversely enlarged portion 5, similar in shape to the aperture 2a in Fig. 1, which has corresponding portions 3a, 4a and 5a. The member 1 is also provided in spaced relation to the aperture 2 with an elongated aperture 6 which is in shape similar to the aperture 6a in the tuyère plate shown in Fig. 1.

Each tuyère plate proper comprises a normally flat or substantially level section 7, having a curved forward surface 8 to render the plate fan-shaped at the forward or discharge end, 30 parallel sides 9, and an abruptly terminating rear end portion 10 which upon its under side may be beveled as at 11. Extending downwardly from the laterally opposite sides 9 of said tuyère plate are parallel walls 12, which taper upwardly 35 and rearwardly at 13 and at their lower edges 14 rest directly upon the upper surface 15 of the lower member 1 or a lower tuyère plate.

The forward portion of each tuyère plate is provided with an integral downwardly extending 40 locking tongue 16, having a rearwardly positioned relatively wide body portion 17, and a forwardly extending transversely reduced portion 18, which in turn tapers toward a forwardly extending edge 19, the increased width of the rear 45 portion 17 at the lower extremity of said last-named portion projecting forwardly to form an L-shaped extension 20 upon each of the opposite sides of said forward portion 18, as clearly 50 shown in Figs. 1, 3 and 4. The rear central portion of each tuyère plate is also provided with an integral depending stud 21, the lowermost surface 22 of which rests directly upon the upper 55 surface 15 of the member 1 or as in actual practice a lower tuyère plate, said stud being pro-

vided with a reduced integral projection 23 which extends normally into the aperture 6 (Fig. 3) of the member 1 or in practice into the aperture 6^a in the body of a lower tuyère plate, as shown in 5 Fig. 1.

A series of plates is built up in an upwardly and rearwardly extending diagonal alignment, with the tongue 16 extending through the aperture 2^a of a lower tuyère plate and with the 10 projection 23 extending into the aperture 6^a, also in the next lower tuyère plate. In this position it will be noticed that said tongue is in a forward position with the L extensions 20 extending beneath and engaging the under surface 15 of the tuyère plate 7 upon the laterally opposite sides of the narrower portion 3^a of the aperture 2^a, and with the forward tongue edge 19 positioned in the forward edge 4^a of said aperture. In this position, a tuyère plate cannot 20 be raised and released from operative local engagement with a lower tuyère plate, since it cannot be moved longitudinally thereof due to the stud 23 being positioned within the aperture 6^a.

However, in order to release a tuyère plate 25 from a supporting tuyère plate there beneath, the rear portion 10 of the upper tuyère plate is raised into the dot-and-dash position 24 (Fig. 2), in order to release the stud 23 from within the aperture 6^a. It is then easy to slide the upper 30 tuyère plate longitudinally rearwardly until not only the enlarged portion 17, but the L-shaped extensions 20 of the tongue 16, have retreated into the enlarged portion 5^a of the aperture 2^a, when the forward portion of the upper tuyère plate 35 may also be removed from engagement with the next lower tuyère plate. Obviously, to replace such upper tuyère plate, or to substitute therefor another tuyère plate, it is only necessary to reverse this operation by inserting the 40 tongue of the upper through the rearmost portion of the forward aperture in the latter and then moving the upper tuyère plate forwardly as far as possible, until the stud of the upper is able to enter the rear aperture of the latter.

Between the forward end portions of the walls 12 and said locking tongue 16, the under side of the tuyère plate body 7 is provided with spaced depending channel-forming ribs tongues partitions of progressively changing shape, each partition 50 extending downwardly into direct contact with the upper surface 15 of the supporting plate (of Fig. 3) or of the next lower tuyère plate. Said last-named partitions are in general divided into two sets 25 and 26. Each of the partitions 55 25 has a forward face in substantial alignment with the forward curved edge portion 8 of the tuyère plate and tapers rearwardly into a decidedly pointed extremity. Each of the intervening partitions 26 forwardly or outwardly is transversely shaped angularly and also tapers into a pointed rear or inner portion. By referring to Fig. 1, it will be noted that in general the oppositely positioned forwardly tapering side surfaces 27 of the partitions 26 cooperate with the 60 similarly converging adjacent surfaces 28 of the pair of partitions 25, between which a given partition 26 is positioned in spaced relation therewith.

With this construction it will be obvious that 70 air under pressure beneath and to the rear of each tuyère plate, when in operative relation to another tuyère plate, is forced outwardly through each pair of converging nozzles 29 or tuyères formed between a pair of the partitions 25 and 75 an intervening partition 26, so that the air drafts

leaving said nozzles tend to cross each other and thereby cause a resulting rotary or swirling motion, similar to the decidedly swirling motion of the air jets passing from the pairs of converging channels in the grate bars described in said Patent No. 1,701,150. 5

It will also be noted that throughout the length of each air channel between adjacent partitions there is no restricted portion beyond which an individual channel expands, so that the combined channel forming partitions 25 and 26 and the locking partition 16 offer but very little resistance to the passage of a relatively large quantity of air outwardly from each tuyère when in operation. The result is that such a large volume of air, radiating from each tuyère plate around its substantially semi-circular forward portion, is free to enter the relatively fine coal 15 commonly used in industrial furnaces, without tending in any way to disturb the body of such 20 coal, or blow it out of the position in which it is intended to burn, or to localize the burning of such coal upon a bank of plates. Instead, this large volume of air as it emerges 25 from between the nozzle-forming plates diffuses in all directions, forwardly, upwardly and laterally, through the body of coal as a result of the swirling motion imparted to each jet, as hereinbefore described, by each pair of converging tuyères. 30

Having in mind the broad principle thus involved, it is to be understood that the invention is not restricted to the exact shape of nozzle-forming partitions here illustrated, but it is applicable to all shapes and arrangements of channels as well as partitions which are so arranged and directed as to bring about the result thus specified. In fact, one reason for making the channel-forming partitions vertically elongated is obviously due to the ease with which a tuyère 40 plate thus shaped may be cast, without requiring any coring other than to provide for the slightly underhanging projections 20 of the locking tongue 16, though by forming the channel-engaging partitions in this manner, it is equally obvious that they thus provide air passages or channels which are capable of passing a very large quantity of air with minimum restriction thereto. 45

Having thus described my invention, what I 50 claim and desire to protect by Letters Patent of the United States is:—

1. A tuyère plate comprising a body portion provided with spaced partitions extending angularly with respect to said body portion, and longitudinally to the free edge of said body, the outer portions of the opposite sides of the alternate partitions converging and of the intervening partitions diverging and operative when spanned by a second such plate to form pairs of intervening tuyères, having outwardly converging terminal portions, operative to direct converging currents of fluid from said tuyère plate. 55

2. A tuyère plate, comprising a body portion, 60 means to detachably secure said tuyère plate to another tuyère plate, and a series of spaced partitions integral with and extending angularly from said body portion towards the normal relative position of a second tuyère plate and longitudinally substantially to the free edge of said first plate, the longitudinal outer portions of the opposite sides of alternative partitions converging and of intervening partitions diverging, to produce relatively isolated pairs of converging 70 75

tuyères, when the channels between said partitions are closed by the second plate.

3. A tuyère plate, comprising a body portion provided with spaced partitions extending angularly and longitudinally substantially to the free edge portion of said body, the outer portions of the opposite sides of the alternate partitions converging and of the intervening partitions diverging and operative when the intervening channels are closed by a second plate to form intervening pairs of tuyères, and locking means carried by said tuyère plate to operatively secure it to a second plate, and said locking means comprising a dividing wall between adjacent angularly disposed tuyères.

4. A tuyère plate, comprising a series of spaced partitions disposed about a portion of its periphery, the opposite sides of alternate partitions diverging outwardly and the corresponding sides of the intervening partitions converging outwardly, the spaces between said partitions being thereby arranged in outwardly converging pairs and forming in effect laterally directed relatively angularly disposed tuyères, cooperating to produce radially directed swirling jets.

5. A tuyère plate of the type adapted to be disposed in a stepped series, the plate being fan-shaped at the discharge end, ribs on one surface of the plate at said end in spaced-apart relation to provide intervening tuyères when the spaces are bridged by the adjacent plate, said ribs at

nately pointed and flared in a plane substantially parallel to the plane of the plate.

6. A tuyère plate of the type adapted to be disposed in a stepped series, ribs on one surface of the plate in spaced-apart relation to provide intervening tuyères when the spaces are bridged by the adjacent plate, said ribs at the discharge ends of the tuyères being alternately pointed and flared in a plane substantially parallel to the plane of the plate.

7. A tuyère plate of the type adapted to be disposed in a stepped series, ribs in spaced-apart relation on one surface of the plate pointed in a plane substantially parallel to the plane of the plate at the forward end of the latter, ribs in alternate relation to the first mentioned ribs on the same surface of the plate spaced from the first mentioned ribs and flared at the forward end of the plate in the aforesaid plane, providing intervening tuyères between the ribs when the spaces are bridged by the adjacent plate.

8. A tuyère plate according to claim 5 wherein the ribs are generally radial from a point intermediate the ends of the plate.

9. A tuyère plate according to claim 7 having means extending below the ribs, to interlock with an adjacent plate.

10. A tuyère plate according to claim 7 having means extending vertically beyond the ribs, to interlock with an adjacent plate.
